(57) **CLAIM**

The ornamental design for flip top cap for a beverage container, as shown and described.

DESCRIPTION

FIG. 1 is a top perspective view of a flip top cap for a beverage container showing my new design.

FIG. 2 is bottom perspective view thereof.

FIG. 3 is front view thereof.

FIG. 4 is a rear view thereof.

FIG. 5 is a left side view thereof.

FIG. 6 is a right side view thereof.

FIG. 7 is a top plan view thereof;

FIG. 8 is a bottom plan view thereof; and,

FIG. 9 is a top perspective view with the flip top in the open position.

The dashed lines depict portions of the flip top cap for a beverage container that form no part of the claimed design. The dot-dash-dot broken lines in FIG. 8 denote the boundaries of the claim and form no part thereof.
